UNITED STATES PATENT OFFICE.

ROBERT WOODMAN, OF MALDEN, MASSACHUSETTS.

TICKET-PUNCH.

SPECIFICATION forming part of Letters Patent No. 392,298, dated November 6, 1882.

Application filed July 20, 1887. Serial No. 244,799. (No model.)

To all whom it may concern:

Be it known that I, ROBERT WOODMAN, of Malden, in the county of Middlesex and State of Massachusetts, have invented certain new and useful Improvements in Ticket-Punches, of which the following is a full, clear, and exact description.

This invention relates to what are commonly known as "ticket-punches," and particularly to that class of such punches employing two jointed lever-arms, one carrying a male and the other a female die, as the direct means of punching the ticket when placed therefor between the jaws.

15 This invention consists in the securing of the male die of the punch to its lever, so that it can be readily removed for being repaired or for insertion of another in its place, as hereinafter described.

20 In the drawings forming part of this specification, Figure 1 is a perspective view of the improved ticket-punch. Fig. 2 is a longitudinal section in detail. Fig. 3 is a perspective view of the clearing device for the male-die

25 part of the punch detached; and Fig. 4 is a detail section, as will hereinafter appear.

In the drawings, A and B represent the two lever-arms of the implement crossing and jointed together intermediately of their length, 30 and the lever B at one end has a male die, C, and the lever A, at one and the same end as that of the lever B, has a female die, D, the two dies co-operating, when the opposite or handle ends, E and F, respectively, of the levers A, B are forced toward each other, to punch 35 the ticket placed between said male and female dies, all as well known and common in ticket-punches.

The male die C consists, in substance, of a 40 prong having the desired and proper shape at its cutting end a, and at its other end it is inserted in a suitably-shaped hole through the lever B, and this end of the lever is split lengthwise to its said hole, as at b, and after the die C is so inserted said split is bound together by a headed screw, d, Fig. 4, entered into and through them, and thus the male die is made fast. Unloosening the screw releases the male die for removal to be repaired or to have another substituted for it.

The lever B, carrying the male die, has a metal spring plate or arm, F, fixed at one end

by its ear-pieces f with screws g to the opposite sides of the lever. This spring-arm F lies within the opening H between the two levers 55 A, B, into which opening the ticket is placed to be punched, and has an opening, h, in it for the male punch C to play through it, and thence it curves upwardly and outwardly, as at L, which curved portion, with the implement at rest, has a bearing, as at M, upon the outside of the lever B. This spring-plate F in the operation of punching operates to clear and free the ticket punched from the male part of the punch as such part leaves the female 65 part. Again, in the separating movement of the two parts of the die after a punching operation, said plate F, by its end overlapping the outer end of the die-lever B, acts as a stop and limit to the opening movement of the dies, 70 and, furthermore, it insures the detachment of the ticket from the male die, because of the vibration imparted thereto in the opening movement of the dies and on the abutment of the outer portion of the lever-arm B against its 75 end overlapping said outer portion.

Between the handle ends E, F of the levers is a spiral spring, N, confined at its opposite end portions upon a prong, O, of each of said levers. This spring in the operation of punching is compressed, and when the pressure on it is released by its reaction the punch-levers are returned to their normal position. Further than this, the spring applied as stated serves the purpose of a handle, as it were, by which 80 85 to suspend the punch from the fingers of the hand.

Having thus described my invention, what I claim, and desire to secure by Letters Patent, is—

In a ticket-punch composed of jaws A, B, having handles and a pivot to fulcrum and a spring to open them, the male jaw having a split, b, at its outer end, and making a seat for a male die, C, in combination with said die C and a 90 binding-screw, g, joining said split b, substantially as described, for the purpose specified.

In testimony whereof I have hereunto set my hand in the presence of two subscribing witnesses.

ROBERT WOODMAN.
